UNITED STATES PATENT OFFICE

GEORGE MONIN, OF LOS ANGELES, CALIFORNIA

DESIGN FOR A WEDDING RING

Application filed September 30, 1930. Serial No. 37,093. Term of patent 3½ years.

To all whom it may concern:

Be it known that I, GEORGE MONIN, a citizen of the United States, residing at Los Angeles, in the county of Los Angeles and State of California, have invented a new, original, and ornamental Design for a Wedding Ring, of which the following is a specification, reference being had to the accompanying drawings, forming a part thereof.

Fig. 1 shows a perspective view of the wedding ring illustrating my new design.

Fig. 2 shows a plan development of my new design for rings shown in Fig. 1.

I claim:

The ornamental design for a wedding ring substantially as shown.

GEORGE MONIN.
